INVENTOR,
Alfred W. Stanhope
BY Howard A. Smith,
His ATTORNEY.

UNITED STATES PATENT OFFICE.

ALFRED W. STANHOPE, OF DAYTON, OHIO.

ELECTRIC SAFETY-SWITCH.

1,355,179.

Specification of Letters Patent. Patented Oct. 12, 1920.

Application filed January 17, 1920. Serial No. 352,042.

To all whom it may concern:

Be it known that I, ALFRED W. STANHOPE, a citizen of the United States, residing at Dayton, in the county of Montgomery and 5 State of Ohio, have invented certain new and useful Improvements in Electric Safety-Switches, of which the following is a specification.

The principal object of my invention is 10 to provide means for automatically holding open, after an emergency plunger has been depressed, an electric safety switch that is commonly employed to shut off the current in machines after an accident has occurred. 15 In switches of the type disclosed in the drawing, the plunger, in the absence of an automatic stop, must be held down by the hand to keep the circuit open long enough to bring to rest the machine in which an operative's limb may have been caught.

It has been found by experience that when an accident occurs, and the plunger depressed, pressure is removed from it too quickly to open the circuit long enough to 25 stop the machine. This is often due to the fact that an operative who is caught in a machine, is unable to hold the plunger down after it has been depressed. Therefore, my improved means have been devised for automatically holding the switch open after the 30 plunger thereof has been depressed.

The preferred form of embodiment of my invention is illustrated in the accompanying drawing, of which Figure 1 is a side elevational view of a safety switch showing the 35 position of my improved automatic stop therein before the plunger has been depressed. Fig. 2 is a side elevational view of that portion of the switch which contains the automatic stop, showing how the plunger is held in its depressed position by the 40 automatic stop. Fig. 3 is a detail sectional view showing the position of the rotatable contact with reference to the fixed ones when the circuit is held open by the automatic stop. Fig. 4 is a detail sectional view 45 showing the position of the rotatable contact with reference to the fixed ones when the circuit is closed by the switch. And Fig. 5 is a side sectional view taken on the line 5-5 of Fig. 1.

Throughout the specification and drawings, similar reference characters denote corresponding parts.

55 In a detailed description of the preferred form of embodiment of my invention, the

numeral 1 designates a switch box that is preferably rectangular in cross section. Integral with the inner upper portions of the end walls of said box, are two oppositely disposed lugs 2, 2 that receive a transverse spindle 3 around which turn the limbs 4, 4 of a horizontal supporting piece 5. The right limb 4 terminates in a right-angled portion that is bent upwardly at right angles, near the right lug 2, to provide an arm 6 through whose lower part the spindle 3 loosely projects. Secured upon the upper horizontal part of the piece 5 is an elongated insulating block 7 from the top face of which there projects a metallic contact tongue 8. As shown in Figs. 1 and 4, the contact tongue 8 in an inclined position is adapted to engage the curved spring ends of a pair of contact members 9, 9 fixedly secured at their inner ends to an insulating block 10 fixedly secured within the casing 1. When the contact members 9, 9 are engaged at their forward ends by the tongue 8, an electric circuit is completed through it and 80 the contact members 9, 9 in the usual way.

For the purpose of opening this circuit, the insulating block 7 is turned to a position about the spindle 3 to withdraw the tongue 8 from engagement with the contacts 9, 9 as 85 shown in Figs. 2 and 3, by the following means. Pivoted to the outer end of the arm 6 is a roller 11 which is received between sleeves 12 and 13 fixedly secured to a plunger 14. The sleeve 12 projects upwardly 90 through a boss 15 and the top of the casing 1 with whose under surface said boss is integral, said sleeve terminating in a head 16.

The lower end of the plunger 14 projects through a coil spring 17 into a boss 18 integral with the bottom of the switch box 1. The lower end of said spring 17 rests in a cupped member 19 supported by the boss 18, while the top of said spring presses upwardly against a cupped piece 20 that encircles the plunger and bears against the sleeve 13 on the latter.

When the plunger 14 is depressed against the tension of the spring 17, the sleeves 12 and 13 will force downwardly the roller 11 between them, to cause the arm 6 which carries it to turn the insulating block about the spindle 3 a sufficient distance to bring the contact tongue 8 out of engagement with the contacts 9, 9 as shown in Figs. 2 and 3, for the purpose of opening the circuit that is established through said contacts and a ma-

chine not shown. If it were not for my improved automatic stop now to be described, the spring 17 would force the plunger 14 upwardly to its circuit closing position when 5 the pressure thereon is removed.

Referring to Figs. 1 and 2, there is secured within a transverse hole in the right end wall of the switch box 1, a tubular insulating member 21 that terminates outside 10 the wall of the switch box in a disk-shaped flange portion 22 which is secured to said wall by screws 23. Projecting loosely through the tubular member 21 is a plunger 24 encircling which, behind a collar 25, is 15 a coil spring 26 adapted to exert its pressure against the collar 25 to force the front end of the plunger across the path of upward movement of the outer end of the arm 6 after the plunger 14 has been depressed. 20 The plunger 14 is thereby held in its depressed position automatically to hold open the circuit through the switch until the plunger 24 is withdrawn from engagement with the arm 6 by a knurled disk 27 on the 25 outer end of the plunger. When the plunger 24 is drawn outwardly, the coil spring 26 surrounding it between the collar 25 and the interior portion of the tubular member 21, is compressed by the outer end of the 30 arm 6 whose side face is now engaged by the front end of the plunger 24. Then when the plunger 14 is again depressed to open the switch circuit, the outer end of the arm 6 will be carried below the front end of the 35 plunger 24, whereupon the spring 17 will force said plunger end across the path of upward movement of the arm 6 automatically to hold the circuit open until the plunger 24 is again drawn inwardly. An 40 operative who may be accidentally caught in a machine is thus assured that when the plunger 14 is depressed to open the circuit for the purpose of stopping the machine, the circuit will be held open by my improved 45 automatic stop after pressure upon the plunger has been removed.

Having described my invention, I claim:

1. In an electric safety switch, the combination with a pair of spaced fixed contacts, 50 of a rotatable contact adapted to be turned into and out of engagement with the fixed contacts to close and open the switch circuit, a plunger, an arm for turning said rotatable contact, means on said plunger adapted, when the plunger is depressed, to move said arm downwardly to turn the rotatable contact out of engagement with the fixed contacts, a spring for returning said plunger, and through it the rotatable contact, to its 55 circuit-closing position, a stop member, and means adapted to project said stop member 60

automatically across the path of upward movement of said arm, to prevent the return of the rotatable contact to its circuit-closing position until said stop member is withdrawn from its position above said arm. 65

2. In an electric safety switch, the combination with a pair of spaced fixed contacts, of a rotatable contact adapted to be turned into and out of engagement with the fixed 70 contacts to close and open the switch circuit, a plunger, an arm for turning said rotatable contact, means on said plunger adapted, when the plunger is depressed, to move said arm downwardly to turn the rotatable contact out of engagement with the fixed contacts, a spring for returning said plunger, and through it the rotatable contact, to its circuit-closing position, a tubular member, a plunger movable through said tubular 75 member across the path of upward movement of said arm when the first plunger is depressed, and a spring encircling the second plunger for forcing its front end automatically above said arm to prevent the return of the rotatable contact to its circuit-closing position until said second plunger is withdrawn from said arm engaging position. 80

3. In a device of the type described, the combination with a switch box, of a pair of contacts fixedly secured therein, a rotatable contact adapted to be turned into and out of engagement with the fixed contacts to close and open the switch circuit, a plunger, 90 an arm for turning said rotatable contact, means on said plunger adapted, when the plunger is depressed, to move said arm downwardly to turn the rotatable contact out of engagement with the fixed contacts, 95 a spring for returning said plunger, and through it the rotatable contact, to its circuit-closing position, a tubular member transversely projected through a hole in said box opposite said arm, a flange on the outer 100 end of said tubular member, secured to said box, a plunger movable through said tubular member, a collar on the front end of said plunger, and a coil spring encircling said second plunger between said collar and the 110 interior portion of the tubular member, to force the front end of said plunger above said arm when the first plunger is depressed, to prevent the return of the rotatable contact to its circuit-closing position until said 115 second plunger is withdrawn from its position above said arm.

In testimony whereof I have hereunto set my hand this 14th day of January, 1920.

ALFRED W. STANHOPE.

Witness:

HOWARD S. SMITH.
